(57) **CLAIM**

The ornamental design for a set of a liquid and lotion applicator with replaceable components, as shown and described.

DESCRIPTION

FIG. 1 illustrates a front perspective view of a first embodiment of a liquid and lotion applicator from the set of a liquid and lotion applicator with replaceable components; FIG. 2 illustrates a perspective view of one of the replaceable components;

FIG. 3 illustrates a perspective view of another replaceable component;

FIG. 4 illustrates a perspective further view of another replaceable components;

FIG. 5 illustrates a perspective view of a further replaceable component;

FIG. 6 illustrates a perspective view of another replaceable component;

FIG. 7 illustrates a perspective view of a further replaceable component;

FIG. 8 illustrates a perspective view of yet another replaceable component;

FIG. 9 illustrates a front perspective view of a second embodiment of the liquid and lotion applicator from the set of a liquid and lotion applicator with replaceable components;

FIG. 10 illustrates a further replaceable components;

FIG. 11 illustrates another replaceable component;

FIG. 12 illustrates a further replaceable component;

FIG. 13 illustrates another replaceable components;

FIG. 14 illustrates yet another replaceable component;

FIG. 15 illustrates still another replaceable component;

FIG. 16 illustrates yet another replaceable component; and,

FIG. 17 illustrates a front perspective view of a third embodiment of the liquid and lotion applicator from the set of a liquid and lotion applicator with replaceable components.
